Attorney.

UNITED STATES PATENT OFFICE.

MARTHA B. PRATT, OF ALBANY, NEW YORK.

CAN.

1,252,494.

Specification of Letters Patent.

Patented Jan. 8, 1918.

Application filed January 18, 1917. Serial No. 142,993.

To all whom it may concern:

Be it known that I, MARTHA B. PRATT, a citizen of the United States of America, residing at the city of Albany, in the county 5 of Albany and State of New York, have invented certain new and useful Improvements in Cans, of which the following is a specification.

My invention relates to cans, and the object of my invention is to provide a can adapted to hold milk or other perishable articles, which is so constructed as to maintain its or their temperature for a considerable length of time; together with such other 15 elements and combinations as are herein-after more particularly set forth.

I accomplish these objects as illustrated in the accompanying drawing, in which:

Figure 1 is an elevation, partly in section, 20 of my invention.

Fig. 2 is a cross section.

Similar letters refer to similar parts throughout the several views.

I am aware that so-called vacuum cans 25 have heretofore been constructed in which there is a space between the can proper and an enveloping casing, with a means for exhausting the air from this space. Cans constructed in this way have to be made of very 30 heavy material in order that the walls adjacent to the space should not collapse, and in order to prevent air from entering the vacuum space they have to be constructed with great care and at considerable expense.

The inner wall, A, or what I call the wall 35 of the can proper, is at one end curved, its walls brought closer together and provided with a flaring neck, B. The flange, C, on the cover, D, enters the opening in the top of 40 the can, and the flaring neck is covered by the curved downwardly projecting flange, E, on the cover, D. On the cover I have provided the space, d, formed by the plate, e, extending across the cover, slightly spaced 45 from the top thereof.

Around the exterior of the wall, A, I place 50 a series of bands or ridges, a, separated from each other and projecting from the wall as shown in the figures.

Around the wall, A, separated therefrom, 55 but engaging the ridges or projections, a, is a casing, F, which may be soldered or otherwise secured to the wall, A, at or near its intersection with the neck, B, as shown in Fig.

1. At the lower or opposite end from the neck, the casing, F, may be secured to the

flange, b, extending downwardly from the bottom, G, by means of a bolt or rivet, H, which passes through the casing, F, and through an angle bar, J, through the flange, 60 b, and the reinforcing ring, K, as shown in Fig. 1, or in any suitable manner.

On the bottom, G, of the can and spaced therefrom is placed the false bottom, L, which is provided with a flange, M, which 65 rests upon the bottom, G, and against the side wall, A, of the can. Beneath the bottom, G, through the casing, F, I preferably place the openings, g. The angle bar, J, 70 acts as a support for the lower portion of the wall, A, engaging the exterior of said wall and interior of the casing, F, and held by means of the bolts, H, as already described.

It will be noticed that the continuity of 75 the space between the wall, A, and the casing, F, is interrupted by the ridges, a, extending around the wall, A, and there is thus a prevention of the circulation of air from the bottom to the top of said space. When air 80 is heated its tendency is to rise; if it is prevented from rising the circulation of the heated air is impossible. The result is that the air will not heat so rapidly, will not convey its heat and acts simply as "dead" air. 85 In the space between the false bottom, L, and the bottom, G, there is no particular tendency of the circulation of the air. The same may be said of the space, d, in the cover, D. 90

I do not limit myself to the number of projecting ridges, a, nor to the material or shape of my can, and by the use of the word "can" I wish to be understood as including any package or container.

I have shown an annular projecting portion, N, which, of course, may be omitted or changed as desired.

I do not limit myself to the arrangement of the flange, M, on the false bottom, L, which is shown and described as resting upon the bottom, G, as it may be arranged differently without departing from the spirit of my invention.

When I refer to an angle bar, I do not 105 wish to limit myself to one of any particular length or size, nor is it necessary that it should be fastened by means of a bolt or bolts.

What I claim as my invention and desire 110 to secure by Letters Patent is:

A can comprising a receptacle; a series of annular projecting ridges connected there-

with; a bottom provided with a downwardly projecting flange; an enveloping casing engaging said projections; an angle bar engaging with the wall of the receptacle
5 and also with the wall of the casing; an annular reinforcing ring engaging the flange extending from the bottom of the receptacle; means for securing the casing, angle bar, flange and ring together; a false bottom placed in the receptacle; a cover pro-

vided for the receptacle; and a plate extending across the cover forming a space between the top of the cover and said plate, substantially as described.

In testimony whereof I have affixed my 15
signature in the presence of two witnesses.

MARTHA B. PRATT.

Witnesses:

G. LE ROY BUTLER,
ARTHUR E. PRATT.
